[57] CLAIM

The ornamental design for a motorcycle handlebar, as shown.

DESCRIPTION

FIG. 1 is a top plan view of a motorcycle handlebar showing my new design;

FIG. 2 is a front elevational view thereof;

FIG. 3 is a bottom plan view thereof;

FIG. 4 is a rear elevational view thereof;

FIG. 5 is a left side elevational view thereof;

FIG. 6 is a right side elevational view thereof; and

FIG. 7 is a sectional view thereof, taken along line 7—7 of FIG. 2, it being understood that the outer end of the handlebar has been omitted for convenience of illustration.
